CLAIM

The ornamental design for a retail display, as shown and described.

DESCRIPTION

FIG. 1 is a top front perspective view of a retail display showing the claimed design;

FIG. 2 is a bottom front perspective view thereof; and,

FIG. 3 is a front view thereof.

The dashed broken lines in the figures show portions of the retail display that form no part of the claimed design.

The dot-dash broken lines in the figures show boundaries that form no part of the claimed design.

Portions of the retail display that are not shown form no part of the claimed design.
